UNITED STATES PATENT OFFICE.

MARK L. SPERRY, OF WATERBURY, CONNECTICUT, ASSIGNOR TO THE SCOVILL MANUFACTURING COMPANY, OF SAME PLACE.

DESIGN FOR AN OIL-CAN.

SPECIFICATION forming part of Design No. 27,748, dated October 19, 1897.

Application filed August 4, 1897. Serial No. 647,129. Term of patent 7 years.

To all whom it may concern:

Be it known that I, MARK L. SPERRY, of Waterbury, in the county of New Haven and State of Connecticut, have invented a new 5 Design for the Bodies of Oil-Cans; and I do hereby declare the following, when taken in connection with the accompanying drawings and the letters of reference marked thereon, to be a full, clear, and exact description of the 10 same, and which said drawings constitute part of this specification, and represent, in—

Figure 1, a side view of an oil-can embodying my design; Fig. 2, a top view of the same.

This invention relates to a design for the 15 bodies of oil-cans, and the design consists in the shape of the neckless body, as shown in the accompanying illustrations.

As herein shown, the design consists of a 20 low body circular in cross-section, and around the body, slightly below its center, is an annular rib *a*, below which the base *b* turns slightly

inward and above which the top *c* curves gradually upward, inward, and again upward to a narrow flange *d*, as shown. Above the flange rises a cylindrical cap *e*, having a 25 slightly crowning top. It will be particularly observed that the body of the can appears to have no neck, and that the plain curve of its upper portion appears to directly support the said flange. 30

I claim—

The design for the bodies of oil-cans as described and shown in the accompanying illustrations.

In testimony whereof I have signed this 35 specification in the presence of two subscribing witnesses.

MARK L. SPERRY.

Witnesses:
